(57) **CLAIM**

The ornamental design for a booster regulator, as shown and described.

DESCRIPTION

FIG. 1 shows a front elevation view of a booster regulator showing my new design;

FIG. 2 shows a rear elevation view thereof;

FIG. 3 shows a right side elevation view thereof;

FIG. 4 shows a left side elevation view thereof;

FIG. 5 shows a top plan view thereof;

FIG. 6 shows a bottom plan view thereof;

FIG. 7 shows a top, front and right side perspective view thereof;

FIG. 8 shows a bottom, rear and left side perspective view thereof; and,

FIG. 9 shows the booster regulator and a tank with pressure gauges.

The portions of the design shown in broken lines in FIG. 1 and FIG. 9 are for the purpose of illustrating the environment only and form no part of the claimed design.
